United States Patent

Des. 236,884
Patented Sept. 23, 1975

236,884

ELECTRONIC BALANCE

Clyde E. Lotter, Stevensville, Mich., assignor to
Leco Corporation, St. Joseph, Mich.

Filed Feb. 16, 1973, Ser. No. 333,048

Term of patent 14 years

Int. Cl. D10—04

U.S. Cl. D10—87

FIG. 1.

FIG. 2.

FIG. 3.

FIG. 4.

FIG. 5.

FIG. 1 is a front perspective view of an electronic balance showing my new design;

FIG. 2 is a front elevational view thereof;

FIG. 3 is a right side elevational view thereof, the left side being a mirror image thereto;

FIG. 4 is a rear elevational view thereof;

FIG. 5 is a top plan view thereof.

I claim:

The ornamental design for an electronic balance, substantially as shown and described.
